STRAND MATERIAL STORAGE DEVICE

Edward W. Ertner, Berwyn, Ill., assignor to Western Electric Company, Incorporated, New York, N. Y., a corporation of New York

Application March 5, 1948, Serial No. 13,313

2 Claims. (Cl. 205—22)

1

This invention relates to strand material storage devices and more particularly to such a device for use on a wire drawing machine.

An object of the invention is to provide a simple and efficient device for storing a looped length of a traveling wire.

In accordance with one embodiment of the invention, as applied to a strand processing, and more particularly to a wire drawing machine in which the wire to be processed is drawn from a supply reel, there is provided, between the wire supply reel and the first drawing capstan, a device comprising two sets of multi-grooved sheaves mounted one above the other, and axially displaced one from the other, on a support retained in operative position on the machine and readily releasable therefrom by means of a fixed pin engaging in a forked lower end of the support and a pair of fixed spring clips engaging the upper end of the support. The wire to be stored is looped back and forth between the two sheaves so that at all times there is a sufficient ever-changing length of wire stored on the device so that in case the wire breaks between the device and the supply reel, or if the reel becomes empty, sufficient wire will be stored on the device to permit and facilitate the handling and brazing or otherwise joining together of the ends of the broken wires or of the inner end of the wire from an empty reel to the outer end of the wire on a full supply reel without restraining the machine.

Other objects and advantages of the invention will more fully appear from the following detailed description taken in conjunction with the accompanying drawing, in which

Fig. 1 is a fragmentary front elevational view of a wire drawing machine showing the wire storing device embodying the features of this invention applied thereto;

Fig. 2 is an enlarged front elevational view of a portion of Fig. 1;

Fig. 3 is a side elevational view of Fig. 2 as viewed looking at the right side thereof; and

Fig. 4 is a horizontal detail sectional view taken on the line 4—4 of Fig. 2.

Referring to the drawing in detail and particularly to Fig. 1, a framework, shown fragmentarily, is indicated generally at 10 for supporting the various elements of a wire drawing machine to which the wire storage device, indicated in general at 11, embodying the features of this invention is shown applied. A compartment 12 within the framework 10 is provided with an opening 13 in its front wall, which is

2

adapted to be closed by a door (not shown). Rotatably mounted in the compartment 12 are a plurality of capstans 17—17, each capstan being provided with a plurality of feeding surfaces of gradually increasing diameters. An up-ended reel 18, shown fragmentarily, containing a supply of relatively coarse wire 19 to be drawn into a smaller diameter in the operation of the wire drawing machine, is stationarily carried on the framework 10 adjacent the bottom thereof. Rotatably mounted on the upper end of the reel 18 is a flyer 20 having an eye 21 at its outer free end through which the wire 19 is guided as it is withdrawn from the reel 18 by the capstans 17—17, the flyer revolving around the stationary reel as the wire is withdrawn therefrom. From the flyer eye 21, the wire 19 passes through an annular guide 24 fixed to a horizontal member 25 of the framework 10. After passing through the guide 24, the wire 19 travels through a guide or wiping die 26 fixed as indicated at 27 in the upper portion of the annular guide 24 and thence through an aperture 28 in the horizontal member 25. From the aperture 28, the wire travels vertically upwards and is looped back and forth upon the wire storage device 11, from which it travels through a sealing device 29 mounted on a horizontal bottom wall 30 of the compartment 12 and into the compartment and thence to and around the smallest diameter of the upper right hand capstan 17 and after its association with the various diameters of each of the capstans 17, dies and other elements of the wire drawing apparatus is directed to a take-up reel (not shown). A more detailed disclosure and description of the capstans 17—17 and the driving mechanism therefor and other elements of the apparatus have been omitted from the present application for the sake of simplicity, since a full description thereof is not essential to a complete understanding of the present invention.

The wire storage device 11, shown in detail in Figs. 2, 3 and 4, comprises a vertically disposed support member 31 of channel-shaped cross section, to the web portion of which are fixed, as indicated at 32, two vertically aligned shouldered stud shafts 33 and 34. Freely rotatably carried on each of the stud shafts 33 and 34 is a multi-grooved sheave 37, the grooves being indicated at 38. Collars 39 and 40 of slightly different lengths surround the shafts 33 and 34, respectively, and at opposite ends abut opposed surfaces of the support member 31 and washers 41, which also surround the shafts and abut the sheaves 37. This arrangement provides for a slight displace-

ment of the sheaves 37, which are identical one with the other, as clearly shown in Fig. 2, so that the corresponding grooves 38 of the sheaves are suitably out of alignment. Welded to the lower end of the support member 31 is a filler block 42, which is fitted between the spaced arms thereof and abuts the web portion. Formed in the web portion and the block 42 and extending longitudinally of the support member 31 is an open slot 44 for receiving a horizontally arranged pin 45 fixed at opposite ends to parallel bifurcations 46 of a bracket 47 fixed to the horizontal member 25 of the framework 10, the spacing between the bifurcations being such that the support member may be freely received therebetween.

In line with the bracket 47 and welded to the lower surface of the bottom wall 38 of the compartment 12 is a U-shaped member 48 having parallel arms 51 spaced apart similar to the bifurcations 46 of the bracket 47 for freely receiving the support member 31 therebetween. Welded to the outer surfaces of the arms 51 of the member 48 is a pair of spring clips 52 having their outer end portions bent toward each other and then at right angles outwardly, as clearly shown in Fig. 4. Welded to the upper end of the support member 31 and arranged in a manner similar to that of the block 42 at the lower end thereof is a filler block 53. It will be apparent that when the slotted end of the support member 31 is aligned with the bifurcations 46 of the bracket 47 while held at an angle to the left of its position shown in Fig. 3, and is then thrust downward, the pin 45 will be received in the slot 44. Thereafter, upon rocking the support member 31 about the pin 45 in a clockwise direction (Fig. 3), the upper end thereof will engage the yieldable ends of the clips 52 and in a continuing movement will spring the clips apart to permit the support member to move into position between the arms 51 of the member 48, whereupon the clips spring back into their normal positions. Thus the wire storage device 11 will be releasably held in its operative position, as shown in the drawings. To readily remove the device 11 from its supporting pin 45 and spring clips 52, the manipulating movements described above in mounting it in operative position are reversed.

In the use of the wire storage device 11, mounted as described above, on a wire drawing machine of the general type described, the wire 19, after being guided from the supply reel 18 and through the aperture 28 in the horizontal member 25, is directed vertically upwards first to the extreme left hand groove 38 of the upper sheave 37 and looped thereon and thence downwards to the extreme left hand groove 38 of the lower sheave 37 and looped thereunder. From the last-mentioned groove 38 of the lower sheave 37 the wire 19 is directed to the groove 38 of the upper sheave 37 adjacent the previous groove thereof over which the wire was first looped, looped thereover, and from thence the wire is directed to the groove 38 of the lower sheave 37 adjacent the previous groove thereof under which the wire was looped and in a similar manner the wire is looped over and under successive grooves 38 of the upper and lower sheaves 37. From the extreme right hand groove 38 of the lower sheave 37 the wire 19 is directed vertically upwards and through the sealing device 29 into the compartment 12 and thence to and around the smallest diameter of the upper right hand capstan 17 and in the manner previously described finally to a takeup reel. The arrangement of the sheaves 37, one to the other,

as well as to the wiping die 26 and the sealing device 29, as clearly shown in Figs. 2 and 3, results in the wire 19, in traveling from the guide or wiping die 26 to the extreme left hand groove 38 of the upper sheave 37, to move past the lower sheave 37 without engaging the same and also in traveling from the extreme right hand groove of the lower sheave to the sealing die 29 to move past the upper sheave without engaging the same. Thus the wire 19 is not subjected to deleterious friction in traveling to the upper sheave 37 from the wiping die 26, nor in traveling from the lower sheave 37 to the sealing die 29.

By looping the wire 19 back and forth between the two freely rotatable sheaves 37, it will be apparent that a considerable length of wire is stored on the device 11 and it will be realized that the amount of wire stored will depend on the diameter of the sheaves and the number of grooves therein. In the operation of the wire drawing machine, the wire 19 is drawn from the supply reel 18 by the capstans 17 and successively over and under the two sheaves 37 in the form of a plurality of loops to constantly provide an ever-changing length of wire stored on the device 11.

In the event that the wire 19 breaks between the storage device 11 and the supply reel 18, the machine is automatically stopped by the opening of a control circuit, usually embodied in a wire drawing machine of the general type described, which circuit includes the wire 19, for the motors driving the capstans 17 and the takeup reel. Also, when the reel 18 becomes empty, the machine is stopped in a similar manner. In machines of this type, drawing wire at high speed and not equipped with the wire storage device 11, the trailing end of the broken or depleted wire 19 would in an instant be drawn into the compartment 12 and off some of the capstan diameters and through some of the drawing dies by the time the machine comes to a complete stop. This would result in the operator having to restrain the machine back to the takeup reel.

In the case of a machine equipped with the wire storage device 11 and the wire 19 breaks or is depleted, a sufficient length of wire will still be stored on the device so that the trailing end of the broken or depleted wire would still be looped on the device when the machine comes to a complete stop and thus the handling and joining together of the ends of the broken wires or of the joining of the trailing end of the wire to the outer end of the wire on a full supply reel would be greatly facilitated and with no necessity of restringing the machine. This joining of the wire ends may be further facilitated at times by removing the device from the machine and this, it is apparent, is easily effected due to the means employed for releasably retaining the device in operative position on the machine.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. The combination with a wire drawing machine of a unitary device for storing a looped length of a wire traveling to a capstan of a wire drawing machine from a wire supply source comprising a vertical support located below the capstan, a pair of multiple grooved wheels journaled on said support on laterally displaced axes over

and between which the traveling wire engageable in the grooves is looped, the grooves on one wheel being axially displaced from corresponding grooves on the second wheel, means on the machine for detachably and pivotally engaging the lower end of said support, and resilient means on the machine for holding the upper end of the support, said pivotally engaging means and resilient means being effective to retain the device in operative position.

2. The combination with a wire drawing machine of a unitary device for storing a multiple looped constant length of a wire traveling to a capstan of the machine from a wire supply source located below the capstan comprising a vertically arranged supporting member having a lower forked end, a pair of multiple grooved wheels journaled horizontally on the supporting member on laterally displaced axes over and between which the traveling wire engaged in the grooves is looped, the grooves on one wheel being axially

displaced from corresponding grooves on the second wheel, an element on the machine engageable in the forked end of the supporting member, and resilient means on the machine for grasping the upper end of the supporting member, said element and resilient means being effective to retain the device in operative position.
